US0D1083915S

(12) **United States Design Patent** (10) **Patent No.:** **US D1,083,915 S**
Iwamoto et al. (45) **Date of Patent:** **** Jul. 15, 2025**

(54) **CONNECTION DEVICE FOR
COMMUNICATION**

(71) Applicant: **MITUTOYO CORPORATION**,
Kanagawa (JP)

(72) Inventors: **Kenji Iwamoto**, Sagamihara (JP);
Tomoharu Yamada, Yamato (JP)

(73) Assignee: **MITUTOYO CORPORATION**,
Kawasaki (JP)

(**) Term: **15 Years**

(21) Appl. No.: **29/812,240**

(22) Filed: **Oct. 20, 2021**

(30) **Foreign Application Priority Data**

Apr. 20, 2021 (JP) ..... 2021-008390 D
Aug. 20, 2021 (JP) ..... 2021-018012 D

(57) **CLAIM**

The ornamental design for a connection device for communication as shown and described.

DESCRIPTION

FIG. 1 is a front, right-side, top perspective view of a connection device for communication, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear, right-side, top perspective view thereof.

The broken lines depict parts of the connection device for communication that form no part of the claimed design.

1 Claim, 8 Drawing Sheets
